(51) **LOC (7) Cl. 14-02**

CLAIM

(52) **U.S. Cl. D14/436**

The ornamental design for a portable memory card for storage of personal information, as shown.

(58) **Field of Search** D14/435-438,
D14/478-480; 361/736, 737, 686, 752;
257/678, 679; 40/124.1; 283/75, 76, 901;
235/487-495, 441, 442, 443, 375; 174/52.1;
439/135, 140, 76.1; D8/347

DESCRIPTION

(56) **References Cited**

FIG. 1 is an isometric view of a portable memory card for storage of personal information that incorporates the new design, showing the card's top, front side and right side;
FIG. 2 is a top plan view of the memory card;
FIG. 3 is an elevational view of the right and left sides of the memory card;
FIG. 4 is a bottom plan view of the memory card;
FIG. 5 is a rear side elevational view of the memory card;
and,
FIG. 6 is a front side elevational view of the memory card.
